Term of patent 14 years

Int. Cl. D24—99

U.S. Cl. D26—14 J

FIG. 1.

FIG. 3.

FIG. 2.

FIG. 4.

FIG. 5.

FIG. 1 is a top plan view of a hearing aid electrical connector showing my new design;

FIG. 2 is a side elevation view of the left end thereof;

FIG. 3 is a left end elevation view of the left end connector;

FIG. 4 is a bottom plan view of the left end connector; and

FIG. 5 is a right end elevation view of the left end connector.

The connector on the right end is identical to that on the left end and is a mirror image of FIGS. 2-5.

I claim:

The ornamental design for hearing aid electrical connectors, as shown and described.
